US00D586741S

(12) **United States Design Patent**
Song

(10) **Patent No.:** US D586,741 S
(45) **Date of Patent:** ** Feb. 17, 2009

(54) **SMART BATTERY**

(75) Inventor: **David Tan Qing Song**, Fu Tian District (CN)

(73) Assignee: **Telecay Industrial, Ltd**, Shenzhen (CN)

(**) Term: **14 Years**

(21) Appl. No.: **29/318,645**

(22) Filed: **May 23, 2008**

(51) LOC (9) Cl. **13-02**

(52) U.S. Cl. **D13/103**

(58) Field of Classification Search D13/102–106, D13/110, 118–119, 184; 429/96–100, 163, 429/176

See application file for complete search history.

(57) **CLAIM**

The ornamental design for smart battery, as shown and described.

DESCRIPTION

FIG. 1 is a bottom left side isometric view of the battery of the invention;

FIG. 2 is a left side elevational view thereof;

FIG. 3 is a front elevational view thereof;

FIG. 4 is a right side elevational view thereof;

FIG. 5 is a rear elevational view thereof;

FIG. 6 is a bottom plan view thereof;

FIG. 7 is a top plan view thereof; and,

FIG. 8 is an exploded view thereof.

The broken lines shown in the drawings are included for the purpose of illustrating environmental structure and form no part of the claimed design.
